UNITED STATES PATENT OFFICE.

PETER EAGLE, OF WALLINGTON, NEW JERSEY.

HAIR-RETAINING COMB.

Application filed November 19, 1925. Serial No. 70,058.

This invention relates to combs such as are worn by ladies to hold the hair in place, and more particularly to such combs especially designed for wear with bobbed hair, 5 having means for gripping the hair or clamping the hair to itself to prevent the comb from becoming dislodged or lost from the hair.

One object of the invention is to provide 10 a comb of the character described which can be manually and positively operated to firmly and securely grip the hair and will retain its grip upon the hair until manually released.

15 Another object is to provide such a comb having a clasp normally in condition to permit the comb to be freely slipped into and out of the hair and manually and positively operable to grip or clamp itself to the hair 20 where it is automatically held until manually released.

25 Other objects are to provide a comb of this character formed of one piece of resilient material folded upon itself to form a body portion and a clasp portion between 30 which the hair may be firmly clamped by manual pressure of the clasp toward the body, manually releasable catches being provided for automatically holding the clasp in 35 clamping position; to provide such a comb having cooperating novel gripping surfaces on the clasp portion and the body portion; to provide a comb which is simple and inexpensive, and to obtain other results and advantages as may be brought out by the following description.

40 Referring to the accompanying drawings, in which corresponding and like parts are designated throughout the several views by the same reference characters,

45 Figure 1 is a plan view of the blank of which the comb is formed;

Figure 2 is a front elevation of the comb; Figure 3 is a rear elevation thereof;

45 Figure 4 is an enlarged transverse vertical sectional view, taken on the line 4—4 of Figure 2, showing the clasp portion in released position;

50 Figure 5 is a similar view showing the clasp portion in clamping position and indicating the relation of the comb to the hair;

Figure 6 is a horizontal sectional view, taken on the line 6—6 of Figure 2;

55 Figure 7 is an enlarged rear elevation of the comb showing a modification of the invention, and

Figure 8 is a transverse sectional view, taken on the line 8—8 of Figure 7.

Specifically describing the illustrated embodiment of the invention, the comb is 60 formed of a single piece A of resilient sheet material, such as celluloid, metal or the like, which is formed at one longitudinal side edge with a plurality of teeth 1. Preferably there are two series B and C of teeth 65 which converge inwardly toward each other.

At an intermediate point in its width the sheet A is formed with a plurality of aligned slots spaced longitudinally from each other and the end edges of the sheet to provide 70 relatively narrow hinge straps 3, and the sheet is returned or folded upon itself at said straps to form a body portion D and a clasp portion E which partially overlies the teeth 1. The clasp portion E is normally 75 held by the inherent resiliency of the hinge straps 3 in spaced relation and at an angle to the body portion D as shown in Figure 5, but may be manually pressed toward the body portion as shown in Figure 6 to clamp 80 hair between itself and the body portion.

85 Any suitable means may be provided for holding the clasp portion in clamping position, but preferably the body portion is formed with a spring tongue catch 4 to engage the edge of an opening 5 in the clasp portion adjacent its free edge, the catch 4 automatically snapping over the edge of said opening as the clasp portion is pressed toward the body portion. The catch 4 may 90 be released by manually pressing or springing it out of engagement with the clasp portion.

95 The comb is preferably longitudinally curved to more or less conform to the head of the wearer, and accordingly the end edges of the body portion may be provided with inturned spring tongue catches 6 to receive the end edges of the clasp portion beneath them to further clamp the clasp portion against the body portion. The edges of the clasp portion automatically snap beneath the tongues 6 as the clasp portion is pressed toward the body portion, and the clasp portion is released from the tongues by longitudinally springing or flexing the comb.

100 To apply the comb to the hair, the clasp portion is permitted to assume the spaced relation to the body portion as shown in Figure 5 and the comb is inserted into the hair as is the ordinary comb. The clasp portion E is then pressed by the hand of

the wearer toward the body portion until the catches 4 and 6 engage the clasp portion. The hair is thus securely gripped between the clasp portion and the body portion and 5 the comb is held against dislodgment. The inclination of the teeth 1 tends to concentrate and closely arrange the hairs beneath the clasp portion so that they are more securely gripped than would be the case if 10 the teeth were parallel and also tends to restrain the tendency of the comb to fall or slide downwardly.

To release the comb from the hair, the comb is longitudinally flexed by simultaneously pressing longitudinally upon both 15 ends thereof which releases the catches 6, and the tongue 4 is pressed out of engagement with the clasp portion, whereupon the resiliency of the sheet causes the clasp portion to spring away from the body portion. 20

To provide a more secure clamping of the comb to the hair, the two series of teeth may be formed with diagonal converging 25 depressions or grooves 7 and the clasp portion may be formed with corresponding series 8 of projections or ribs to enter said depressions or grooves whereby the hair is crimped when the clasp portion is forced against the body portion, as shown in Figures 7 and 8.

While I have shown the invention embodied in certain details of construction, it will be understood that this is primarily for the purpose of illustrating the principles 35 of the invention and that many modifications and changes can be made in said details without departing from the spirit or scope of the invention. Therefore, I do not desire to be understood as limiting myself 40 except as required by the following claims when construed in the light of the prior art.

Having thus described the invention, what I claim is:

1. A hair retaining comb comprising a 45 body portion having teeth at one edge thereof, a clasp portion connected to said body portion partially overlying said teeth and normally resiliently influenced away from and held in spaced relation to said body portion, said clasp portion being capable of being manually forced toward said body portion to clamp hair between them, and manually releasable means for holding said clasp portion in hair clamping relation to said body portion.

2. A hair retaining comb comprising a 50 body portion of resilient material having teeth at one edge thereof and a clasp portion at the opposite edge normally resili-

ently held in spaced angular relation to the 60 body portion and partially overlying said teeth, said clasp portion being capable of being manually moved toward said body portion to clamp hair between them, said body portion and said clasp portion being 65 longitudinally curved and one thereof being formed at its end edges with inturned spring tongues to receive the edge of the other beneath them, whereby said tongues hold said clasp portion in clamping relation to said body portion and said clasp portion may be released by simultaneous pressure upon opposite ends of the comb longitudinally thereof.

3. A hair retaining comb comprising a 70 body portion having teeth at one edge thereof, a clasp portion connected and normally resiliently held in spaced relation to said body portion and partially overlying said teeth, said clasp portion and said teeth having cooperating projections and recesses to crimp the hair between them when the clasp portion is in clamping position, said clasp portion being capable of movement toward 75 said body portion to clamp hair between them, and manually releasable means for holding said clasp portion in hair clamping relation to said body portion.

4. A hair retaining comb comprising a 80 body portion of resilient material having teeth at one edge thereof and a clasp portion at the opposite edge normally resili- 85 ently held in spaced angular relation to the body portion and partially overlying said teeth, said clasp portion and said teeth having cooperating projections and recesses to crimp the hair between them when the clasp portion is in clamping position, said clasp portion being capable of movement toward 90 said body portion to clamp hair between them, and manually releasable means for holding said clasp portion in hair clamping relation to said body portion.

5. A hair retaining comb comprising a 95 body portion having teeth at one edge thereof, a clasp portion connected and normally resiliently held in spaced relation to said body portion and partially overlying said teeth, said teeth having diagonal grooves and said clasp portion having corresponding 100 diagonal ribs to crimp the hair when the clasp portion is in clamping position, said clasp portion being capable of movement toward 105 said body portion to clamp hair between them, and manually releasable means for holding said clasp portion in hair clamping relation to said body portion.

PETER EAGLE.
